UNITED STATES PATENT OFFICE.

CHARLES LIONEL MARCUS, OF NEW YORK, N. Y.

ATOMIZER.

Application filed March 25, 1927, Serial No. 178,249, and in France February 3, 1927.

This invention relates to spraying devices such as atomizers adapted to be used for toilette, medicinal and the like purposes.

One object of the invention is the provision 5 of an atomizer of improved compact construction which is particularly adapted to form a toilette accessory for dispensing a liquid perfume.

Another object of the invention is the provision 10 of an improved atomizer of the character described having a rubber bulb provided with novel means for collapsing same to supply air for spraying.

A further object of the invention is the provision 15 of a device of the character described having an improved adjustable means for regulating the spraying effect of the device.

A still further object of the invention is to 20 provide a device of the character described comprising few and simple parts, which shall form when assembled an ornamental toilette accessory, which shall be cheap to manufacture, easy and simple to operate, and practical and efficient to a high degree in use.

Other objects of this invention will in part be obvious and in part hereinafter pointed out.

The invention accordingly consists in the 30 features of construction, combinations of elements, and arrangement of parts which will be exemplified in the construction hereinafter described, and of which the scope of application will be indicated in the following claims.

In the accompanying drawing, in which is shown one of the various possible illustrative 35 embodiments of this invention,

Fig. 1 is a vertical sectional view showing the internal construction of a liquid perfume 40 spraying device embodying the invention;

Fig. 2 is a front elevational view thereof; and

Figs. 3 and 4 are cross-sectional views taken on lines 3-3 and 4-4 in Fig. 1 showing, 45 respectively, the construction of a regulator member and nozzle support.

Referring in detail to the drawing, 10 denotes a spraying device embodying the invention adapted to dispense liquid perfumes, medicines or the like. Said device is seen to comprise a container or bottle 11 made of suitable material preferably porcelain or glass for holding a supply of liquid perfume 12 to be sprayed from an atomizer 13 mounted to 50 form a closure for the top opening 11^a of the bottle 11.

To secure said atomizer 13 in position, a connecting collar 14 is fixedly secured in any well known manner, as by cementing to a shoulder portion 11^b on the rim of the bottle 60 opening 11^a. Said collar is internally threaded as at 14^a to engage an external thread 13^a of the atomizer casing 13^b. The collar is also formed with an upstanding ledge 14^b adapted to fit into a peripheral groove 13^c in the atomizer casing 13^b when the latter is screwed into the collar 14 as shown in Fig. 1.

The atomizer casing 13^b may be cylindrical in shape and has a transversely extending partition wall 13^d formed with an outwardly 70 concaved center portion which serves as a seat 13^e for a rubber bulb 15. The seat 13^e has a tubular portion 16 axially extending downwardly therefrom into the bottle, and a nipple 17 formed with a peripheral lip 17^a is 75 threaded into the seat 13^e so that the lip projects into the concavity above the seat. The bulb 15 has an opening 15^a to receive said lip, and the cooperation of the parts is such that when the bulb engages with the lip of 80 the nipple, the seat 13^e conforms to the contour of the bulb and forms a rigid support therefor. If now the bulb is collapsed, air will be forced therefrom through the bore 16^a of the tube 16 into the bottle 11.

A regulator 18 is provided at the lower end of the tubular portion 16 to control the flow of air into the bottle. Said regulator includes a cap 19 having a wall portion 19^a which may be provided with suitable means for engaging 90 the lower end of the tubular portion 16. A plurality of holes 19^b are bored through the wall portion 19^a adjacent the end of the tubular portion 16 thus constituting adjustable means for throttling said holes 19^b in proportion as the regulator cap 19 is screwed up or down on the end of the tubular portion. The bore 16^a of the tube 16 is enlarged at its lower end as shown at 16^b to provide a chamber from which the supply of air may flow through said 95 holes 19^b into the bottle 11.

The atomizer 13 also has a nozzle 20 having an orifice member 20^a which may be integrally constructed with the casing 13^b. Said member 20^a has communication with the bottle 105 above the level of the liquid so as to freely receive air therefrom. For dispensing the liquid from the bottle an outlet tube 20^b is provided, said tube having its lower or intake end submerged in the liquid 12 and its upper end or outlet 20^c extending into the member 20^a in coaxial relation therewith, leaving an 110

annular passageway for the air. The outlet tube 20^a may be secured in position to the casing 13^a by soldering as at 21, and by a spider 22 within the member 20^a. The member 20⁵ may be threaded externally to engage a closure cap 23 which can be secured to the atomizer casing 13^a by any suitable means such as by a chain 24.

For collapsing the bulb 15, a pressure lid 10¹⁰ 25 is provided to reciprocate in the casing 13^a and forms therewith a chamber to enclose the bulb. To permit the bulb to be readily collapsed, the pressure lid is constructed to have a central downwardly extending projection 15 or finger 25^a which concentrates the pressure exerted on the lid to collapse the bulb easily. A spring 26 returns the pressure lid to its normal position, and a ring member 27 which is threaded to the casing 13^a releasably 20²⁰ retains the lid in the casing, said ring member 27 extending beyond a shoulder portion 25^b of the lid to serve as a stop for the latter as will be clear from Fig. 1. An air valve 28 permits the bulb to fill with air in the usual 25 manner.

The operation of the device 10 is now apparent. On depressing the pressure lid, the finger 25^a contacting with the rubber bulb 15 collapses the latter against the seat 13^a. The 30 air in the bulb is forced through holes 19^b in the cap 19 into the bottle 11 where pressure will be exerted on the surface of the liquid 12 and cause the same to rise and flow out of the tube 20^b. Simultaneously, air will flow 35 through the member 20^a to render a fine atomization of the liquid being sprayed from the outlet end of the tube 20^b.

If a greater spraying effect is desired, the 40 regulator cap 19 is adjusted to increase the size of the opening at the holes 19^b, thus providing for greater spraying of the liquid 12 and causing a correspondingly increased flow of air through nozzle 20.

When the device 10 is used as an accessory 45 forming a part of a traveling outfit the bottle may be filled with liquid and the regulator cap 19 screwed up to completely close the holes 19^b therein. If accidental pressure should be exerted on the pressure lid, the contents of 50 the bottle will not be placed under pressure by the air from the bulb and no liquid will be accidentally sprayed from the bottle. With the cap 23 in place on the nozzle 20 and the regulator cap screwed tightly in closed position 55 absolute safety against accidental spillage of the liquid from the bottle is assured.

A dominant feature of this invention resides in the means provided for supplying the air pressure to dispense and atomize the liquid. It will be noted from the foregoing description that in accordance with this invention no pump or other like mechanism visible to the user or extending from the device is employed. The pressure lid 25 is at 60 all times substantially within the top casing 65

13^a and never extends further outward from the casing than shown in the drawing, thus forming a substantially flush closure for the casing and cooperating with the member 27 to make an ornamental cover for the container as a whole. By reason of this construction, 70 the device may be easily operated with one hand and presents to the user a neat, compact appearance such as is required to make it suitable for a lady's dressing table or boudoir. 75

It will thus be seen that there is provided a device in which the several objects of this invention are achieved, and which is well adapted to meet the conditions of practical use. 80

As various possible embodiments might be made of the above invention, and as various changes might be made in the embodiment above set forth, it is to be understood that all matter herein set forth or shown in the 85 accompanying drawing is to be interpreted as illustrative and not in a limiting sense.

Having thus described my invention, I claim as new and desire to secure by Letters Patent:

1. An atomizer comprising a container, means for spraying liquid from the container, said spraying means including a bulb to supply air under pressure to the container, a regulator connected with the bulb 90 including a tubular portion, a cap fitted over the end of the tubular portion and having an opening communicating with said container, the effective size of said opening being adjustable to control the flow of air from said bulb, and a tube leading from said container, said tube being positioned to have one end submerged in liquid in the container, and a nozzle associated with the other end of said outlet tube and providing a passage for air 100 under pressure from the container to finely atomize the liquid ejected from the outlet end of said tube.

2. A device having means for attachment to the open end of a liquid container, consisting of a casing, a partition in said casing, a collapsible member mounted on said partition, a movable wall in said casing for compressing said collapsible member, and spring means mounted on said partition for 110 returning said wall from compressing position.

3. A spraying device comprising an atomizer mounted on a liquid container, said atomizer having a bulb means for spraying liquid from said container, a pair of telescoping members forming a chamber surrounding the bulb, one of said members when depressed being adapted to collapse the bulb for operating the spraying means, and resilient means positioned in said chamber normally urging said compressible member in its outermost position. 115 120 125

In testimony whereof I affix my signature.
CHARLES LIONEL MARCUS.
